US00D902733S

(12) United States Design Patent (10) Patent No.: US D902,733 S
Baker et al. (45) Date of Patent: * Nov. 24, 2020

(54) BOTTLE

(71) Applicant: Isle of Wight Distillery Ltd, Ryde (GB)

(72) Inventors: Xavier Baker, Ventnor (GB); Benjamin Phalen Oates, Tunbridge Wells (GB); Philip Alan Marlow, Oxted (GB)

() Term: 15 Years

(21) Appl. No.: 35/507,340

(22) Filed: May 7, 2019

(80) Hague Agreement Data

Int. Filing Date: May 7, 2019

Int. Reg. No.: DM/202450

Int. Reg. Date: May 7, 2019

Int. Reg. Pub. Date: Aug. 30, 2019

(51) LOC (12) Cl. 09-01

(52) U.S. Cl.

USPC D9/555; D9/544

(58) Field of Classification Search

USPC D7/300, 300.1, 598; D9/504, 505, 516, D9/519, 520, 522, 529, 530, 537, D9/544-546, 549, 554, 556, 558, 563, D9/564, 567, 568, 574, 686, 688, 690, D9/691, 555

CPC B65D 1/00; B65D 1/02; B65D 1/0223; B65D 23/00; B65D 81/00; B65D 2501/00; B65D 2501/0009
